A. A. WILLIAMS,
ATTACHMENT FOR OPERATING ACCELERATORS OF AUTOMOBILES, &c.
APPLICATION FILED APR. 10, 1919.

Patented July 8, 1919.

UNITED STATES PATENT OFFICE.

ALLEN A. WILLIAMS, OF LOELOCK, NEBRASKA.

ATTACHMENT FOR OPERATING ACCELERATORS OF AUTOMOBILES, &c.

1,309,347.

Specification of Letters Patent.

Patented July 8, 1919.

Application filed April 10, 1919. Serial No. 289,072.

To all whom it may concern:

Be it known that I, ALLEN A. WILLIAMS, a citizen of the United States, residing at Lovelock, in the county of Humboldt and 5 State of Nebraska, have invented certain new and useful Improvements in Attachments for Operating Accelerators of Automobiles, &c.; and I hereby declare that the following is a full, clear, and exact description thereof, reference being had to the accompanying drawings, which form part of this specification:

This invention is a novel attachment for use in automobiles to assist the driver in 15 controlling the accelerator. In automobiles the engine is usually provided with a fuel supply valve that is operatively connected with a lever or rod which projects into the machine within reach of the operator's foot 20 so that he can by slight pressure of his foot on such accelerator cause an increased supply of fuel to the engine when he desires to increase the speed or power of the machine; varying the supply by varying the 25 pressure upon said accelerator.

The accelerator as ordinarily constructed is or iron and becomes very hot when the machine is used for a long time; rendering it very uncomfortable for the operator and 30 frequently causing foot trouble when driving a long distance or a long period of time without stopping. Furthermore, the driver's foot is apt to be jarred off the lever on rough roads, and to prevent this he has 35 to keep his foot in a more or less cramped or rigid position and under tension in order to keep it in contact with the accelerator.

The object of my invention is to provide an attachment which will prevent the transmission of heat from the accelerator to the 40 foot of the driver; lessen wear on the driver's shoe; provide a firm brace for the foot; and support the weight of the driver's leg comfortably; and relieve his foot and leg 45 of cramping strains, and enable him to maintain easy control of the accelerator for long periods of time without having his foot become unduly heated, or cramped, and without liability of his foot being jarred out of 50 control of the accelerator on rough roads, and to enable the operator to feed the gas steadily when driving over rough roads without having to resort to the hand control.

The invention consists in the novel attach-

ment illustrated in the accompanying drawings and hereinafter described and claimed. 55

In the drawings:

Figure 1 is a perspective view of the complete attachment.

Fig. 2 is a side elevation showing the attachment in position for use. 60

Fig. 3 is a detail longitudinal section through the heel portion of the attachment.

Fig. 4 is a detail transverse section on line 4-4, Fig. 2. 65

The attachment as shown comprises a support and hinge member, having a base portion 1 adapted to be secured to the bottom of the vehicle adjacent the accelerator by any suitable means, such as bolts 1^a passed 70 through openings in the portion 1. This member can be readily secured in the machine at a point most comfortable for the driver, as indicated in Fig. 2, when seated in the car. At the front end of this base portion 1 is an upstanding member or standard 1^a, preferably formed integral with the base 1 and provided on its upper edge with hinge pintles 1^b between which is pivotally secured the accelerator operating pedal. 80

This accelerator operating pedal is preferably made of metal, and comprises a heel portion 3, a shank portion 4, and a head or presser portion 5; all preferably formed integral or rigidly connected. 85

The heel portion 3 of the pedal is preferably in a plane below the shank portion 4, and is connected with the rear end of the shank portion by an upstanding flange or part 3^a, which at its junction with the shank portion is provided with a perforation for the passage of the hinge pin 2^c; the part 3^a forms the hinge member of the pedal and is fitted between the pintles 2^b of the standard, and supports the heel portion 3 in a 90 plane below the pin 2^c, and the shank portion 4 and head 5 being preferably in a plane somewhat above the heel portion. 95

The upper surface of the complete pedal approximately conforms to the under surface of the shoe of the operator, which rests thereupon as indicated in dotted lines, Fig. 2, so that the weight of the foot upon the pedal is borne by the heel and the head portions thereof and no direct pressure is 100 exerted on the shank or arch of the foot. 105

The heel portion 3 is also provided with an upstanding flange 3^e at its rear end,

adapted to engage the rear end of the heel of the operator's shoe and assist in retaining the foot easily in position on the pedal. The heel portion 3 is also provided with a depressed portion 3^c, adjacent the flange 3^a, approximately conforming to the shape of the lower part of the heel of a woman's shoe, so that when the accelerator pedal is used by a woman, the heel of her shoe will engage the recess and her foot be thereby easily retained in position on the pedal.

The shank portion 4 is preferably slightly curved downwardly adjacent hinge pin 2^c, and then projects forward to the head 5, so that it will not cause any pressure upon the shank of the shoe or arch of the foot of the operator. The shank is also preferably narrow so as not to interfere with the operation of the brake lever.

20 The presser head 5 is of sufficient size, and preferably circular, to insure its engagement with the accelerator, and also to afford a substantial surface contact or bearing for the sole of the operator's shoe.

25 My presser head 5 is preferably provided with a heat insulating plate 5^a of wood, or other suitable material; and with a surface wear-plate 5^b of rubber, or other suitable material, to contact with the sole of the shoe.

30 The metal head 5 itself forms a metal wear-plate contacting with the accelerator.

The presser head is so positioned relatively to the heel and shank portions of the pedal that it will fit neatly under the sole 35 of the driver's shoe, as indicated in Fig. 2.

The support 1—1^a is secured to the floor of the automobile or vehicle in rear of and adjacent to the accelerator which is adapted to be depressed by the foot of the driver, 40 and in some cases has a metal disk or head 4^a on its end to be engaged by the foot of the driver. This accelerator becomes hot, when used continuously for sometime and is apt to burn the shoe in contact therewith, and 45 uncomfortably heat the foot of the driver; but when my attachment is properly secured adjacent to and in rear of the accelerator the head 5 will rest lightly upon the accelerator, and the operator can easily control the accelerator by rocking his foot slightly or 50 pressing upon the head 5, and his foot is protected from the heated accelerator and kept cool by the non-heat conductor plate 5^a on the presser head.

55 As shown the heel of the operator rests upon the plate 3 and presses against the standard 1^a, as indicated in Fig. 2; and the standard 1^a provides a firm support for the pedal and a brace against which the front 60 of the driver's heel bears, and this gives the driver a steady control of the accelerator even on rough roads. The standard 1^a rises in front of the heel of the shoe, and under the instep of the shoe resting upon the 65 pedal, while member 5 rests easily upon the

accelerator; and the driver can by slightly depressing his toe depress the member 5 and through it the accelerator.

With this construction the driver's foot will be supported by the pedal upon the 70 standard, and he can readily control the accelerator by more or less depressing the head 5.

The usual control spring, (not shown,) of the accelerator can be set so as to easily 75 counterbalance the light weight of the head 5, and render the pedal very sensitive to action.

To regulate the normal position of the head 5 of the pedal relative to the accelerator lever, an adjustable stop bolt 6 may be tapped through the base 1, as shown in Fig. 3, the head of this bolt, engaging the under-side of the heel portion 3, limits the depression of the heel of the pedal and correspondingly limits the elevation of the presser head 5; so that the pedal can be adjusted to suit various heights of accelerator levers, or the projection of such levers above the floor of the car, and render the pedal sensitive in 90 action upon the accelerator, and have no unnecessary lost or idle motion.

The plate 5 insulates the shoe from the hot accelerator, and keeps the foot of the wearer cool, and at the same time provides 95 a substantial broad member for engagement by the foot of the driver; and the driver does not have to hold his foot in a cramped position in order to keep full control of the accelerator.

A material advantage of the invention is that the driver's heel is supported on the pedal in rear of the hinge connection, and he can brace his foot solidly against the standard and by simply slightly depressing 105 his toe he can control the accelerator in the same manner as he would if the device were not present, but with greater certainty of operation when riding on rough roads, and with a great deal more comfort, as he can 110 rock the pedal upon the standard; the heel rising as the toe descends, but not to so great an extent; this obviates the necessity of the operator's bending the toe portion of his foot in order to depress the head 5 and accelerator. At the same time, by reason of 115 the peculiar connection or shape of the heel and instep portions of the pedal, the operator can brace his foot and leg firmly against the standard on which the pedal is pivoted 120 and easily control the accelerator at all times.

What I claim is:

1. An attachment for the purpose specified; comprising a member adapted to be 125 secured to the floor of an automobile adjacent the accelerator and having an upstanding portion providing a brace for the heel of the operator; and a pedal member having a heel portion, a shank portion and a presser 130

head; said pedal being hinged to the standard, the heel portion lying below the hinge pintle, and the presser head over the accelerator.

5 2. An attachment for the purpose specified; comprising a member adapted to be secured to the floor of the automobile adjacent the accelerator and having an upstanding portion providing a brace for the heel of the operator; and a pedal member having a heel portion, a shank portion and a presser head, the heel portion of the pedal having a depressed portion for engagement of the heel of a woman's shoe; said pedal being hinged to the standard, the heel portion lying below the hinge, and the presser head over the accelerator.

10 3. An attachment for the purpose specified; comprising a member adapted to be secured to the floor of an automobile adjacent the accelerator and having an upstanding portion providing a brace for the heel of the operator; a pedal member having a heel portion, a shank portion and a presser head, having a non-heat conducting cover plate on its upper side; said pedal being hinged to the standard, the heel portion lying below the hinge, and the presser head over the accelerator, substantially as described.

15 4. An attachment for the purpose specified; comprising a member adapted to be se-

cured to the floor of an automobile adjacent the accelerator and having an upstanding portion providing a brace for the heel of the operator; a pedal member having a heel portion, a shank portion and a presser head, said shank being narrower than the heel or presser head; said pedal being hinged to the standard, the heel portion lying below the hinge, and the presser head over the ac- 40 celerator.

20 5. An attachment for the purpose specified; comprising a member adapted to be secured to the floor of an automobile adjacent the accelerator and having an upstanding 45 portion providing a brace for the heel of the operator; a pedal member having a heel portion, a shank portion and a presser head; the heel portion of the pedal having a flange at its rear end, and a depressed portion for 50 engagement at the heel of a woman's shoe; said head having a non-heat conducting cover plate on its upper side; and said shank being narrower than the heel or presser head; said pedal being hinged to the stand- 55 ard at the junction of the heel and shank portions, and the heel portion lying below the hinge pintle, and the presser head over the accelerator.

25 In testimony that I claim the foregoing as 60 my own, I affix my signature.

ALLEN A. WILLIAMS.
